FLUSHING VALVE FOR TOILET TANKS

James Castellano, New York, N. Y.

Application October 24, 1950, Serial No. 191,791

4 Claims. (Cl. 4—67)

1

This invention relates to a new and improved valve control means for flush tanks for toilets, its prime object being the provision of novel valve control means, whereby the amount of water discharged therefrom may be controlled. This is accomplished by a novel construction of the valve stem, by means of which it is possible to prematurely re-seat the flushing valve at any point during a flushing operation.

Every time a conventional flush tank is operated, the water contents thereof must drop until it substantially reaches the level of the valve seat of the flush outlet at the bottom of the tank before the buoyant valve is seated, thereby concluding a single flushing operation. This means that once the tank handle is actuated most of the water in the tank is discharged, as there are no means in the conventional flush tanks for regulating or controlling the amount of the water discharged during a flushing operation. In the course of a single flushing operation, at least five gallons of water are discharged each time. This is obviously an unnecessary waste of water, as in many instances only a small amount of water is required for effective flushing.

It is therefore the principal object of this invention to provide simple and novel valve control means for flush tanks, whereby the operator may stop the discharge of the water in the tank at any time during a flushing operation, thereby controlling the amount of water discharged at will. The said valve control means can thus be readily actuated to move the buoyant valve into its seat, when the water in the tank is at any level above the said seat.

Other and additional objects and advantages of the invention are as follows:

(a) Water is greatly conserved, without sacrificing the full requirements of complete sanitation;

(b) Overflow of the toilet bowl can be prevented when the bowl becomes stopped or clogged;

(c) The improved control means can readily be installed in all existing types of flush tanks;

(d) The said control means may be produced at low cost;

(e) The said control means are simple and effective in operation and highly effective in conserving water; and

(f) Entanglement of the valve stem is avoided.

Other objects of the invention will be set forth in the following description and drawings, in which:

Fig. 1 is an elevational view of the essential

2

parts of a flush assembly embodying the invention, the buoyant valve being seated in its valve seat, and the actuating handle being in its normal horizontal inoperative position;

5 Fig. 2 is a view similar to Fig. 1, but illustrating the buoyant valve in its raised or flushing position;

Fig. 3 is a perspective view of the improved valve stem assembled with the lifting wire link;

10 Fig. 4 is a view similar to Fig. 3, showing however a slightly modified form of valve stem; and

Fig. 5 is a view also similar to Fig. 3, but showing still another modification of valve stem.

15 Only those parts of the flush tank essential to illustrate the invention have been shown.

Referring to Figs. 1 and 2 of the drawing, 10 represents the usual discharge or flushing outlet of a conventional flush tank, the upper end 11 of said outlet constituting a seat for the buoyant valve 12. A vertical overflow pipe 13 communicates with said outlet 10 through the lateral extension 14.

20 A guide bracket 15 is secured to overflow pipe 13, the outer end of said bracket being yoke-shaped to form a pair of aligned guide bearings 15a and 15b through which extends the vertically disposed valve stem 16. The said guides retain the said valve stem in vertical alignment with the axis of valve seat 11.

25 The lower threaded end 16a of valve stem 16 is threadedly connected to the upper end of buoyant valve 12, so that when said valve stem is lifted the said buoyant valve is raised therewith. A lifting rod or wire link 17 has slideable connection with said valve stem 16. Wire link 17 is raised by the lever or valve-trip arm 18, the upper end 17a of said link being inserted into one of the three small openings 18a formed in the inner end of said lever and then bent downwardly to pivotally connect the said link to the said lever. The lower end of said link 17 is formed with the lateral eye 17b for engagement with valve stem 16, which will hereinafter be more fully described.

30 The invention herein resides in the improved form of valve stem, which is employed in the flush assembly to meter the water to be discharged from the flush tank. For the first embodiment of valve stem, reference is made to Figs. 1 to 3 of the drawings. In this embodiment, the upper end of valve stem 16 is formed with an eye 16b for holding the said valve stem and its asso-

45 A handle 19 is connected to the outer end of lever 18, by means of which the said lever may be operated.

50 The invention herein resides in the improved form of valve stem, which is employed in the flush assembly to meter the water to be discharged from the flush tank. For the first embodiment of valve stem, reference is made to Figs. 1 to 3 of the drawings. In this embodiment, the upper end of valve stem 16 is formed with an eye 16b for holding the said valve stem and its asso-

55 for holding the said valve stem and its asso-

Fig. 1 is an elevational view of the essential

ciated lifting link 17 in assembled relationship. Disposed on valve stem 16 below its integral eye 16b and spaced therefrom is the flat circular metal member 16c, the connection being by soldering or any other suitable means. The said member 16c plays an important role in the control means, as will hereinafter be described.

It will be noted that circular member 16c is always disposed above the guide bearings 15a and 15b, and that eye 17b of lifting link 17 is always disposed intermediate eye 16b and member 16c of the valve stem 16. As will hereinafter be explained, said eye 17b is slideable on the upper portion of valve stem 16 intermediate eye 16b and member 16c.

As will be understood, the spacing of stop members 16b and 17b is such that eye 17b is capable of a lost-motion action longitudinally of the stem. Also, that lever 18 is so dimensioned and proportioned as to provide a dominant weight factor in favor of the link-attached end, with the link attached to the lever in such manner that the link will move with the lever during the pivotal movement of the latter in either direction. However, as indicated in Fig. 2, the lever weight factor is of lower value than that of the buoyancy factor of valve 12. As a result of these conditions, the eye 17b will normally rest idly upon the lower stop member 16c when the lever is not being operated manually to raise the valve, and is not being manually moved downward during premature closing. Hence, the assembly is readily manually operative to raise the valve from its seated position of Fig. 1, with the eye 17b being moved into contact with the upper stop member, with the lever releasable after the valve has been raised sufficiently to clear the suction-affecting zone of the outlet, or into contact with the member 15b. On such release, the lever, link and eye move to such idle position due to the lever weight factor. In such idle position the eye 17b and lower stop member 16c are in contact and therefore capable of providing forcible downward movement for premature closing immediately upon beginning the upward movement of handle 19, enabling the user to exercise the "at will" control the assembly is designed to provide.

Referring to Fig. 4, the lifting link and valve stem are substantially the same as just described in Figs. 1 to 3, save for a slight modification in the upper portion of the valve stem. In this embodiment, eye 16b has been replaced by the nut 26b. To accommodate the said nut, the upper end 26a of valve stem 26 has been threaded.

Referring to Fig. 5, it will be noted that the eye 16b and the circular metal member 16c of the valve stem 16 illustrated in Figs. 1 to 3 have been replaced by the small nuts 36b and 36c respectively. To accommodate the said nuts the upper portion 36a of valve stem 36 has been threaded.

As eye 16b and circular member 16c of Figs. 1 to 3 perform precisely the same function as nut 26b and circular member 26c of Fig. 4 and also the two spaced small nuts 36b and 36c, the following description of the operation of the valve control means of Figs. 1 to 3 will apply to the slightly modified forms of Figs. 4 and 5.

Fig. 1 shows the buoyant valve 12 seated in its seat 11. In this inoperative or non-flushing position, lateral eye 17b of the wire link member 17 will rest on circular member 16c, as shown in broken lines. The full lines of said eye 17b and link member 17 show the starting position from

the said rest position. The starting of the flushing operation is commenced by depressing handle 19 downwardly. When this is done, lever 18 and its depending link member 17 are raised in unison, thereby raising and unseating the ball valve 12. The said buoyant valve will thus be raised to its uppermost position, with its top end abutting the bottom end of lower guide bearing 15b. In this flushing position, link member 17 will assume a vertical position, with the ball valve being supported by the water in the tank.

By reason of the buoyancy of valve 12, normally the said valve would remain elevated until it was drawn on its valve seat 11 by the suction 15 produced by the weight of the descending water level. However, by reason of the improved construction, it is a very simple matter to overcome the buoyancy of said valve and re-seat the same when the water in the tank is at any level above 20 its valve seat. This can be accomplished, at any time, during a flushing operation merely by pushing handle 19 upwardly. When this is done, link member 17 is returned to the position shown in broken lines in Fig. 1, thereby causing lateral eye 17b to impinge and strike against the circular member 16c of valve stem 16, thus forcing ball valve 12 into its seat 11, and stopping the exit of the water from the tank. Fig. 2 shows the flush assembly ready for the premature seating of the ball valve as lateral eye 17b of link member 17 is resting on circular member 16c of valve stem 16. In this manner, the water discharge can be curtailed or metered at any desired water level above the level of the valve seat. 30 In other words, flush valve 12 may be prematurely seated at any time during a flushing operation at the will of the user. Said valve may be thus closed at any time before the full quantity of the water in the tank is discharged.

It will be noted that eye 16b and circular member 16c of valve stem 16 also act as upper and lower stops to respectively limit the upward and downward movement of eye 17b on said valve stem.

45 It will be understood that the improved valve stem that constitutes the essence of the invention may be varied without departing from the spirit of the invention. It likewise may be altered as existing installations may require.

50 What is claimed is:

1. The combination of a flush tank having a discharge outlet, a valve means for controlling the discharge of water through said outlet, said means including a valve stem having its upper 55 end provided with a pair of axially aligned stop members, and longitudinally spaced manual means for moving the valve and its stem between the valve open and closed positions at will, said latter means including a pivoted lever and a link carried thereby, said link having its lower end formed with an eye slidably mounted on the valve stem between said stop members and having a lost motion relation to said stop members, said manual means being operative to raise the stem 60 toward its valve-open position by cooperation of the link eye with the upper stop member for normal flushing operation, said manual means being operative at will to prematurely close the opened valve by pressure engagement between the link-eye and the lower stop member to thereby forcibly move the valve and its stem to valve-closed position.

2. A combination as in claim 1 characterized in that the pivoted lever is formed and mounted 65 to position the link eye as resting idly on the

lower stop member in the normal inactive position of the lever, pivotal movement of the lever in the desired direction serving to open the valve or to provide premature closing thereof dependent upon the direction of such pivotal movement from an idling position.

3. A combination as in claim 1 characterized in that the upper end of the valve stem is threaded to detachably receive the upper stop member to permit ready assembly of link and stem and to permit variation of the spacing distance between the stop members.

4. A combination as in claim 1 characterized in that the upper end of the stem member is threaded to detachably receive and position the upper and lower stop members thereon to thereby permit ready assembly of the link eye and stem and to permit variation of the spacing distance between the stop members and vary the throw of the manual operating lever.
